4 Claims. (Cl. 103—150)

ABSTRACT OF THE DISCLOSURE

A diaphragm type liquid fuel pump having a fuel in-
let connection dampening pressure pulsations to improve
fuel flow.

SPECIFICATION

This invention relates to fuel pumps and more par-
ticularly to fuel pumps of the diaphragm type such as
are used on automobiles.

It has been customary in the past to employ air domes
for the inlets of many reciprocating diaphragm fuel
pumps, the purpose in mind being to minimize pulsations
in the pump flow and thereby increase and smooth out
the pump discharge. Such a pump is disclosed in the
U.S. Patent 2,419,775 granted Apr. 29, 1947, in the name
of William H. Hazard.

It has now been found that the use of an apertured
tube in an air inlet dome with the aperture of the tube
directed downwardly toward the inlet valve leading to
the diaphragm pumping chamber results in a pronounced
increase in the liquid flow through the pump and as
compared with air inlet domes as employed heretofore
in this field.

An object of the present invention is to provide an
improved fuel pump of the diaphragm type in which
the pulsations are damped and the flow is not disrupted
or impeded by undue turbulence.

A feature of this invention is a diaphragm type fuel
pump in which an apertured inlet tube is so located in
an air inlet dome as to direct flow toward the inlet valve
without disturbing the air or vapor trapped in the dome.

This and other important features of the invention will
now be described in detail in the specification and then
pointed out more particularly in the appended claims.

In the drawings:

FIGURE 1 is an elevation and part sectional view of
a fuel pump as one embodiment of the present invention
and as supported for operation of an automobile
engine; and

FIGURE 2 shows a modification of the inlet dome
arrangement of FIGURE 1.

In FIGURE 1 of the drawings, a portion 10 of an auto-
mobile engine is shown as a support for a fuel pump
body 12 which is attached to the engine 10 as by bolts
14. As is conventional in automobile pumps, the body
12 has a passage 16 in which is mounted a pivot pin 18
and on this pin a rocker arm 20 is adapted to be oscillated
by some portion of the engine such as a cam on the
camshaft. As will be understood and which is conven-
tional in fuel pumps, the rocker arm 20 is adapted by
means of two cooperating backing plates 24 and 26 to
reciprocate a pumping diaphragm indicated at 30. This
diaphragm has its periphery clamped between a rim of
the pump body 12 and a pump cover generally indicated
at 32. The pump cover is composed of an upright sheet
metal dome 34 in the form of an inverted cup, an outer
shell 36 which is crimped as at 38 to the pump body
12 tightly to retain the diaphragm 30 as well as the periph-
ery of an inner shell 40. The outer shell 36 retains the
dome 34 by means of a brazed and tight joint as at 42.

2

The inner shell 40 bears an aperture 44 in alignment
with an aperture 46 in the outer shell 36 so that a one-
way inlet valve 50 supported by the inner shell 40 is in
alignment with both apertures 44 and 46. The valve
50 is not specifically described herein as it is conven-
tional but it will be appreciated that when suction is
induced between the diaphragm 30 and inner shell 40
by reciprocation of the diaphragm 30, the one-way inlet
valve 50 will open and when the pressure in the pump-
ing chamber 60 increases, the inlet valve 50 will close.

An inlet tube 54 extends into the dome 34 and the
length of the tube substantially traverses the full width
of the pulsator chamber formed by that dome but its
width is less than that of the pulsator chamber. It will be
seen in FIGURE 1 that the tube 54 is open at its end
56. An aperture 58 is formed in the bottom side of the
tube 54 and this aperture faces or is directed toward
the inlet valve 50.

The inner shell 40 of the cover 32 not only defines
20 the pumping chamber 60 with the cooperation of the
diaphragm 30 but it also cooperates with the outer shell
36 in forming outlet chamber 62. A sealing washer 37
insures separation of the pump inlet flow from the out-
let chamber 62. Communication between the pumping
25 chamber 60 and the outlet chamber 62 is by way of
a conventional one-way outlet valve 63. Flow from the
outlet chamber 62 of the pump is by way of a fitting
64 and a discharge tube 66.

Cars with a high underhood temperature sometimes
30 require a vapor diverter for satisfactory operation, that
is, to avoid vapor lock of the fuel system. The pump
disclosed in FIGURE 1, therefore, preferably has the
fuel outlet fitting 64 extend down into the lower por-
tion of the outlet chamber 62 where the solid or liquid
35 fuel collects. A small opening 80 is located at the top of
the outlet chamber 62 and through which vapors that
collect above the lower end of the fitting 64 may pass
back by means of a conduit 82 to the fuel tank.

In FIGURE 2, a slight variation in the structure is
40 seen in that the dome 34 is fitted with a different inlet
tube 84. This tube has an aperture 86 similar to the
aperture 58 in FIGURE 1 but in this case the end of
the tube 84 is closed off as at 88.

The dome 34 serves to increase liquid fuel flow through
45 the pump by trapping air and fuel vapors in its top. This
air and vapor in the dome is such as substantially to
reduce the pressure and vacuum peaks thereby allowing
the valves 59 and 63 to follow the strokes of the pump
more effectively.

The tube 54 or 84 helps to maintain the vapor or
air inside the dome 34 and reduces the turbulence in
the liquid fuel which would otherwise occur and serve
to disturb the air or vapor pocket in the dome 34. This
55 reduction of turbulence definitely improves the liquid
flow rate through the pump as has been determined by
experimentation. Wide variations of tube designs, tube
end termination points and tube angles with respect to
the inlet valve 50 axis have been tested departing from
60 those disclosed in the drawings but of all those tested,
the substantial increase in liquid flow was obtained only
by the tube inlet designs disclosed. In comparing the
various inlet tube designs, no changes other than in
the tube inlets were made in the pumps undergoing tests
65 but it is understood that the same advantages are ob-
tained using the inlet arrangement of the present invention
if the outlet fitting 64 were changed also to embody
a dome and inlet tube as employed with regard to the
inlet valve, i.e., many variations may be made in the
outlet arrangement without adversely affecting the per-
70 formance of the tube 54 or 84 with respect to the inlet
valve and dome 34.

I claim:

1. A diaphragm type fuel pump in which a diaphragm and a pump cover define a pumping chamber, inlet and outlet one-way valves retained in said cover, a dome forming a pulsator chamber leading to the inlet side of said inlet valve, an inlet tube extending into said dome and having a diameter less than the width of said pulsator chamber, one side of said inlet tube facing said pulsator chamber, and an aperture in the other side of said inlet tube directed toward said inlet valve.

2. A diaphragm type fuel pump in which a diaphragm and a pump cover define a pumping chamber between them, inlet and outlet one-way valves retained in said cover of said pumping chamber, a dome forming a pulsator chamber leading to the inlet side of said inlet valve, an inlet tube forming a wall partially closing off said pulsator chamber and having an open end, and an aperture in the side of said inlet tube facing and directed toward said inlet valve.

3. A diaphragm type fuel pump in which a diaphragm and a pump cover are clamped together to define a pumping chamber between them, inlet and outlet one-way valves retained in said cover to control flow through said pumping chamber, a dome leading to the inlet side of said inlet valve and forming a part of said cover, an inlet tube having a closed end extending into said dome and having one side substantially traversing said

10 pulsator chamber, and an aperture in the opposite side of said inlet tube directed toward said inlet valve.

5 4. An upright diaphragm type fuel pump in which a diaphragm and a pump cover are clamped together to define between them a pumping chamber, inlet and outlet one-way valves retained in said cover to control fuel flow through said chamber, a vertically extending dome forming a pulsator chamber at the top of said pump and leading to the inlet side of said inlet valve, an inlet tube of smaller width than that of said pulsator chamber extending horizontally and into said dome, an aperture in the bottom side of said inlet tube in alignment with the axis of said inlet valve and coaxial with the latter, and the top side of said inlet tube facing said pulsator chamber.
